ATTORNEY

UNITED STATES PATENT OFFICE.

GUSTAF CARLSON, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

SWITCHBOARD SIGNAL.

1,421,403.

Specification of Letters Patent. Patented July 4, 1922.

Application filed August 22, 1919. Serial No. 319,089.

To all whom it may concern:

Be it known that I, GUSTAF CARLSON, a citizen of the United States, residing at Rochester, in the county of Monroe and State of New York, have invented certain new and useful Improvements in Switchboard Signals, of which the following is a full, clear, concise, and exact description.

This invention relates to means for operating and controlling switchboard signals. In certain types of switchboards the signals, such as the clearing-out signals, are restored by an operator's ringing or listening key, so that after the signal or signals have been displayed to the operator they may be restored to their normal position by an adjustment of said key. As previously constructed these signals and their controlling means were expensive to manufacture and difficult to assemble and maintain in adjustment.

The present invention provides signals and their controlling means which are simple in construction and so mounted that they cannot easily get out of adjustment, at the same time being easy to manufacture and assemble.

Other advantages not herein enumerated will appear from the detailed description and appended claims.

In the drawings, Fig. 1 illustrates a side view of the signals and their controlling means with the parts thereof in normal position.

Fig. 2 is a vertical view of a portion of the structure and shows the means for restoring the signals to normal position.

Fig. 3 shows a lever or connecting link extending between the restoring key and the signals which it controls.

Fig. 4 is a top view of a portion of the structure showing the shield for the signal or shutter.

Referring to the drawings, 5 designates a mounting plate provided with apertures through which a double throw key 6, a depressible key 7 and mechanical signals or shutters 8, operate. This plate is also provided with screw holes for receiving screws by which a spring assembly generally designated 9 is suspended in the brackets 10. Other brackets 11 are also secured by screws (but not shown) to the under side of the mounting plate and are designed to rigidly

hold electromagnets 12 in a vertical position but in spaced relation to said mounting plate. Each electromagnet 12 is provided with an armature 13 pivoted at 14. The armature 13 has a strip of non-magnetic material 22 folded about it to prevent the armature from remaining in engagement with its electromagnet when the energizing force is removed. This strip has a portion 24 struck out to form a notch or catch, and a leaf spring 30 is attached thereto to normally hold the armature away from its electromagnet. The signal or the shutter 8 consists of a vertical plate provided with a downwardly extending latch 15 pivoted to the mounting plate at 16, and protected by a windowed guard 25. The vertical plate is provided with a rearwardly extending curved surface which is distinctively marked to render it readily visible. The latch 15 of the signal when in normal position engages the notch in the strip covering the armature 13.

The means for restoring the signal consists of a link or bar generally designated 16' which is mounted to slide horizontally in notches cut in the brackets 10. This link is provided with struck-out lugs 17, 18 and 20, and with a stop 21 which will be further described. The lug 17 is engaged by a vertical rigid spring 18' mounted in the spring assembly which tends to keep the link 16 in the position shown in Fig. 1. The lug 18 is arranged to be engaged by the roller 19 of the double throw key 6 when this key is moved toward the left, while the lugs 20 are arranged to engage the lower part of the vertical portion of the signals 8, and when the link is moved toward the right the shutters are rotated to their vertical or normal position. The downwardly extending portion 21 serves as a stop when the link is moved toward the left and the shutters 8 limit the reverse movement of the link. It will be seen that the link is provided with an off-set portion to permit its movement without disturbing the re-ring key 7 and the double throw key 6.

It will be understood that the present invention is to be used in connection with an operator's cord circuit and that the various springs of the spring assembly cooperate in the various operations incidental to the establishing of a telephone connec-

tion. These circuits are well known to those skilled in the art and a description of their operation will not be given here.

The springs 22 of the spring assembly 5 which are operated when the key 6 is moved to the left, control contacts which establish a listening condition of the cord circuit, while the set of springs 23 which are controlled when the key is adjusted to the 10 right, close contacts to establish a ringing condition of the telephone cord circuit. The depressible key 7 is provided with a cam 24 which controls contact springs for establishing a so-called ring-back circuit. 15 While the various springs of the spring assembly have been described as co-operating in establishing the listening and ringing condition of the cord circuit and inclosing the ring-back circuit, they may be employed 20 for other purposes or may be differently constructed and arranged without departing from the present invention.

In operation, when either or both of the electromagnets 12 attract their armatures 25 13, the latch 15 of the associated signal or shutter disengages the armature and rotates to the right displaying the curved or indicating surface. When it is desired to restore the shutters to their vertical or normal 30 position, the key 6 is moved toward the left of Fig. 1, bringing the roller 19 into engagement with the lug 18, thereby moving the link 16 toward the right. The lugs 20 engage the lower part of the vertical 35 portion of the shutters and rotate them to their vertical or normal position. When the key 6 is released, the spring 18 moves the link toward the left as far as the stop 21 will permit, so that the shutters will not 40 be encumbered by the lugs 20.

What I claim is:

1. In combination, an operator's key, an electromagnet and an armature adapted to be attracted thereby, a signal adapted to occupy either a displayed or a concealed position, means carried by such armature for normally holding such signal in a concealed position, and means slidably actuated by said operator's key for moving said signal from a displayed to a concealed position.

2. In combination, an operator's key, a vertically disposed electromagnet and an armature adapted to be attracted thereby, a signal adapted to occupy either a displayed or a concealed position, means carried by such armature for normally holding such signal in a concealed position, and means slidably actuated by such operator's key for moving such signal from a displayed to a concealed position.

3. In combination, an operator's key, a vertically disposed electromagnet and a horizontally disposed armature adapted to be attracted thereby, a signal adapted to occupy either a displayed or a concealed po-

sition, means carried by such armature for normally holding such signal in a concealed position, and means slidably actuated by such operator's key for moving such signal from a displayed to a concealed position.

4. In combination, a key, an electromagnet and an armature adapted to be attracted thereby, a shutter, an indicator carried thereby and adapted to occupy either a displayed or a concealed position, means carried by such shutter for engaging such armature when such indicator is in a concealed position, and means slidably operated by such key for moving such indicator from a displayed to a concealed position.

5. In combination, a key, an electromagnet and an armature controlled thereby, a signal mounted to occupy either a displayed or a concealed position, means carried by said armature for normally holding said signal in a concealed position, and a member having portions engaging said key and signal, said member being slidably movable under the control of said key to restore said signal to a concealed position.

6. In combination, a key, an electromagnet and an armature controlled thereby, a signal mounted to occupy either a displayed or a concealed position, means carried by said armature for normally holding said signal in a concealed position, and a member having portions engaging said key and signal, said member being slidably movable horizontally under the control of said key to restore said signal to a concealed position.

7. In combination, a key, electromagnets and an armature for each electromagnet controlled thereby, a plurality of signals mounted to occupy either a displayed or a concealed position, means carried by each armature for normally holding one of said signals in a concealed position, and a member having portions engaging said key and said signals, said member being slidably movable under the control of said key to restore said signal to a concealed position.

8. In combination, a key, an electromagnet and an armature adapted to be attracted thereby, a signal arranged to occupy either a displayed or a concealed position, means carried by said armature for normally holding said signal in a concealed position, and a member slidably mounted for moving said signal from a displayed to a concealed position, and means for operating said member.

9. In an article of the class described, an indicator mounted to rotate to a displayed or a concealed position, an electromagnet having an armature, means controlled by said armature for latching said indicator in its concealed position, and a manually operable member mounted for rectilinear movement for moving said indicator into a position to be latched by said means.

10. In an article of the class described, an indicator mounted to rotate to a displayed or a concealed position, said indicator being provided with a latch, an electromagnet having an armature, said armature being provided with a catch arranged in one position to be engaged by said latch for holding said indicator in its concealed position and in another position of said armature for releasing said indicator into its displayed position, and a manually operable member mounted for rectilinear movement for moving said indicator into such a position that its latch engages said catch. 5 65
15. 11. In an article of the class described, a mounting plate having an opening therein, an indicator mounted adjacent said opening to occupy a concealed or a displayed position, an electromagnet supported on said mounting plate adjacent said indicator, said electromagnet having an armature for holding said indicator in a concealed position and for releasing said indicator into its displayed position, brackets on said mounting plate, said brackets having apertures and a manually adjustable member movable through said apertures for moving said indicator into its concealed position. 20 70
25. 12. In an article of the class described, a mounting plate having an opening therein, an indicator rotatably mounted adjacent said opening to occupy a displayed or a concealed position, said indicator being provided with a latch, an electromagnet having an armature, said armature having a catch to engage said latch and hold said indicator in one position, a spring assembly, apertured brackets for supporting said spring assembly on said mounting plate, a rotatable key supported on said mounting plate for actuating said spring assembly and a member movable in said apertures under the control of said key and provided with means for moving said latch into engagement with said catch. 30 75
35. 13. In an article of the class described, a mounting plate having an opening therein, an indicator mounted adjacent said opening to occupy a displayed or a concealed position, said indicator being provided with a latch, an electromagnet having an armature, said armature having a catch to engage said latch and hold said indicator in one position, a spring assembly, apertured brackets for supporting said spring assembly on said mounting plate, a rotatable key supported on said mounting plate for actuating said spring assembly and a member movable in said apertures under the control of said key and provided with means which engage said key and said indicator whereby the operation of said key will restore said indicator in a position to be latched by said armature, said member being provided with a laterally offset portion so that said member may be positioned at one side of said key. 40 80
45. 14. In an article of the class described, an indicator mounted to rotate to a displayed or a concealed position, a projection on the lowermost part of said indicator, an electromagnet having an armature, means controlled by said armature for latching said indicator in its concealed position, and a manually operated member mounted for rectilinear movement, said member being provided with means to engage said projection for moving said indicator into a position to be latched. 45 85
50. 15. In an article of the class described, a mounting plate having a plurality of openings therein, an indicator adjacent to each opening, said indicator being arranged to occupy a concealed or a displayed position, an electromagnet supported adjacent to each indicator, said electromagnet having an armature for holding its indicator in a concealed position and for releasing said indicator into its displayed position, brackets on said mounting plate, said brackets having apertures and a manually adjusted member movable through said apertures to engage said indicators for moving the same into their concealed positions. 55 90
55. 16. In an article of the class described, a frame, a signal pivoted on said frame, a projection on said signal at one side of said pivot, an indicating surface on said signal at the opposite side of said pivot, an electromagnet having an armature, means controlled by said armature for latching said indicator in its concealed position, and a manually operated member mounted for rectilinear movement for moving said signal into a position to be latched by said armature. 60 95
60. 17. In an article of the class described, a frame, a rotatable key mounted on said frame, a spring assembly mounted adjacent to said key, a roller on said key positioned to actuate said spring assembly during certain adjustments of said key, an indicator mounted on said frame to rotate to a displayed or a concealed position, an electromagnet having an armature, means controlled by said armature for latching said indicator in its concealed position and a member mounted for rectilinear movement to move said indicator into a position to be latched by said means, said member being actuated by the roller on said key. 65 100
65. In witness whereof, I hereunto subscribe my name this 20 day of Aug., A. D. 1919. 70 110
70. GUSTAF CARLSON. 115 120
